UNITED STATES PATENT OFFICE.

BYRON BARDAX, OF NEW YORK, N. Y.

MILK-BOTTLE HOLDER.

Application filed June 5, 1926. Serial No. 113,979.

This invention relates to improvements in milk bottle holders and has for its primary object, the provision of a safe and sanitary means of receiving milk by delivery, as the 5 bottle of milk is automatically locked in a box like housing when placed therein by the milkman, where it is protected from theft and from contact with dogs or cats.

Another object of the invention resides in 10 a box like container having a door therein for the insertion of a bottle of milk to be housed therein, and which door contains a novel form of latch mechanism controlled by the actuation of a bottom, which latch 15 mechanism is normally in an unlocked position to permit of the lifting of the door for the removal of an empty bottle and for the insertion of a full bottle of milk, the weight of the full bottle resting upon the bottom 20 causes the operation of the latch mechanism to automatically lock the door to prevent unauthorized entry to the container.

Another object of the invention is to provide a locked box in which an empty milk 25 bottle may be placed for removal by the milkman, but which automatically locks when a full bottle is inserted to prevent theft of the same.

With these and other objects in view, the 30 invention resides in certain novel construction and combination and arrangement of parts, the essential features of which are hereinafter fully described, are particularly pointed out in the appended claims, and are 35 illustrated in the accompanying drawing, in which:—

Figure 1 is a perspective view of my improved milk bottle container.

Figure 2 is a vertical longitudinal sectional view therethrough, showing the box in an empty condition.

Figure 3 is a similar view but showing the position of the parts when a full bottle of milk is contained therein.

Figure 4 is a horizontal sectional view on the line 4—4 of Figure 3.

Figure 5 is a perspective view of a modified form of my invention.

Referring more particularly to the drawing, the reference numeral 10 designates a box like container having a hinged door 11 in the top wall thereof, and which is spring pressed as at 12 so as to normally keep the same in a closed position. A hinged door 13 is mounted in the front wall of the container and is provided with a key actuated

lock 14 whereby the door may be locked by the owner to prevent unauthorized entry to the interior of the container.

A movable false bottom 15 is arranged 60 within the container and is normally held in a raised position above the true bottom by springs 16 interposed therebetween. Pins 17 depend from the bottom 15 and pass longitudinally through the springs for engagement with the true bottom for limiting the downward movement of the false bottom when a weighted article is placed thereon. A frame 18 overlies the false bottom for limiting upward movement of said bottom, although the tension of the springs 16 is only sufficient to normally hold the false bottom against the frame when an empty bottle is placed thereon.

A latch mechanism 19 is contained on the underside of the door 11 and is operable by a rod 20 extending upward from adjacent the true bottom and parallel to the rear wall of the container. The rod is provided with a hinged angular extension 21 which is pivotally mounted upon the true bottom as at 22, while the free end of the angular extension underlies the false bottom approximately centrally thereof. The weight of the rod holds the head 22' provided on the free end thereof, normally below the plane of the latch mechanism 19 and out of contact therewith. However, should a weighted article such as a full bottle of milk be placed upon the false bottom, the weight of the same 90 overcomes the tension of the springs, thereby causing the false bottom to press downward upon the free end of the angular extension causing the rod to move upward to position the head 22' in the path of the latch mechanism during the closing of the door, whereby to actuate the same for a purpose now to be explained.

The latch mechanism 19 above referred to comprises a housing 23 supported from the underside of the door and in which a carriage or frame 24 is slidably mounted. A spring 25 having one end attached to the carriage and its other end fixed to the housing tends to hold the frame against the inner end of the housing with the tail 26 projecting from the frame through the casing and in an extended position. Slidably mounted in the frame or casing 24 is a bolt 27 normally held in a retracted position with the outer end of the housing, but capable of being extended upon the outward longitudi-

nal movement of the frame for engagement with a keeper 28 on the top wall of the box like casing. The outward longitudinal movement of the frame is provided by the 5 engagement of the tail 26 with the head 22 of the rod when the said head has been raised into the path of movement of the tail during the closing of the door. An expansion spring 29 encircles a reduced shank of the bolt and 10 serves to hold the end of the bolt extended. However, when the bolt is extended by reason of the outward longitudinal movement of the frame, the same is capable of being automatically retracted by reason of an in- 15 clined face 30 on the free end thereof, which engages the top wall of the container prior to the snapping of the bolt into the keeper.

In practice, we shall presume that an empty bottle has been positioned within the 20 container the weight of which is insufficient to cause the actuation of the latch mechanism. The owner after inserting the bottle locks the front door and it is prevented from being opened by an unauthorized person. 25 The milkman in delivering a fresh bottle of milk, lifts the top door and removes the empty bottle from the container and in return inserts a fresh bottle. The weight of this fresh bottle of milk is sufficient to move 30 the false bottom downward to actuate the rod 20 to cause the head 22 to move to a position where it is engaged by the tail of the latch mechanism during the closing of the door and moves the latch bolt to an extended 35 position for engagement with its keeper. It will therefore be seen that the top door is automatically locked and the bottle is housed against theft and against dogs and cats, as it will be appreciated that it is a common 40 occurrence for such animals to lick the milk from the tops of bottles which is unsanitary.

For the purpose of rigidly supporting the container upon a wall or other structure, I provide openings 31 in the rear wall thereof 45 for the passage of screws or like elements.

Springs 32 are connected to the rod 20 and to the rear wall of the casing 10, to hold said bar down to normally keep the member 21 against the false bottom 15 and 50 to assist the springs 16 in supporting said false bottom when an empty bottle is resting thereon. Said springs 16 and 32 yield however when a full bottle is placed upon the false bottom to permit same to drop and lift the rod 20 to actuate the latch mechanism 19 in the manner set forth.

If desired, a single rectangular shaped receptacle A may be provided as shown in Figure 5 for use by occupants of apartments, and in which a plurality of individual lock boxes B and C may be arranged, each independently operable, and which may be identified by the name of the users.

While I have described what I deem to be 60 the most desirable embodiment of my inven-

tion, it is obvious that many of the details may be varied without in any way departing from the spirit of my invention, and I therefore do not limit myself to the exact details of construction herein set forth nor to anything less than the whole of my invention limited only by the appended claims.

What is claimed as new is;—

1. A milk bottle holder comprising a box like container having a hinged door in one wall thereof, a latch bolt slidably mounted on said door, means for normally holding said latch bolt in a retracted position, said means including a spring actuated carriage in which said latch bolt is mounted, a false bottom movable within said box like container, means for yieldingly supporting said false bottom in spaced relation to the true bottom of said container, and means operable upon the downward movement of said false bottom by reason of the placing of a weighted object thereon, for causing the sliding movement of said carriage to move said latch bolt to operative position upon the closing of said door for engagement with a keeper mounted on said container. 75

2. A milk bottle holder comprising a box like container having a hinged door in the top thereof, a carriage slidably mounted on the underside of said door, a spring for normally holding said carriage in a normal retracted position, a spring actuated latch bolt movable with said carriage, a false bottom yieldingly supported above the true bottom of said container, a rod slidably mounted on one of the walls of said container, actuating means for lifting said rod upon the opening of said hinged door and the placing of a weighted object upon said false bottom to move said rod into the path of a tail extending from said carriage whereby closing of said door will cause said tail to engage said rod to slide said carriage to an extended position to move said latch bolt to an operative position to automatically engage a keeper upon the extreme closing of said door to lock said door against being opened while the weighted object remains upon said false bottom, and a key controlled door through which the weighted object may be removed. 90

3. A milk bottle holder comprising a box like container having a hinged door in the top thereof, a carriage slidably mounted on the underside of said door, a spring for normally holding said carriage in a normal retracted position, a spring actuated latch bolt movable with said carriage, a false bottom yieldingly supported above the true bottom of said container, a rod slidably mounted on one of the walls of said container, actuating means for lifting said rod upon the opening of said hinged door and the placing of a weighted object upon said false bottom to move said rod into the path of a tail extend- 100

ing from said carriage whereby closing of said door will cause said tail to engage said rod to slide said carriage to an extended position to move said latch bolt to an operative position to automatically engage a keeper upon the extreme closing of said door to lock said door against being opened while the weighted object remains upon said false bottom, and a key controlled door through which the weighted object may be removed, 10 and means for returning said rod to normal position upon the removal of the weighted object from said false bottom whereby said spring will return said carriage and latch bolt to inoperative position. 15

In testimony whereof I have affixed my signature.

BYRON BARDAX.
